(57) **CLAIM**

(**) Term: **14 Years**

The ornamental design for an environmental enclosure for a vending machine, as shown and described.

(21) Appl. No.: **29/152,535**

DESCRIPTION

(22) Filed: **Dec. 19, 2001**

FIG. 1 is a front view of an environmental enclosure for a vending machine according to the present design;

Related U.S. Application Data

FIG. 2 is a top plan view of the environmental enclosure for a vending machine of FIG. 1; and,

(63) Continuation of application No. 29/133,496, filed on Nov. 30, 2000, now Pat. No. Des. 454,401.

FIG. 3 is a left side elevational view of the environmental enclosure for a vending machine of FIG. 1, the right side being a mirror image.

(51) **LOC (7) Cl. 25-02**

The bottom view and rear view of the environmental enclosure for a vending machine have been omitted since they are

(52) **U.S. Cl. D25/58; D25/59**

unornamented and do not form part of the claimed design.
